TENNIS RACKET

José Luis Consiglio, New York, N. Y.

Application June 19, 1936, Serial No. 86,153

6 Claims. (Cl. 273—73)

My invention relates to a new and improved tennis racket, and to a new and improved method of making the same.

One of the objects of my invention is to provide a racket of simple and sturdy construction, and which can be manufactured at low cost.

Another object of my invention is to provide a racket having a frame, which is provided with suitable reinforcing members.

Another object of my invention is to provide a racket having improved means for connecting the frame and said reinforcing members.

Other objects of my invention will be set forth in the following description and drawings, which illustrate preferred embodiments thereof, it being understood that the above statements of the objects of my invention is intended generally to explain the same without limiting it in any manner.

Fig. 1 is a top plan view of a blank which is used for making one embodiment of the invention.

Fig. 2 is a side elevation of Fig. 1.

Fig. 3 is a top plan view of the blank, after the first operation in forming the racket has been completed.

Fig. 4 is a top plan view showing the completed racket.

Fig. 5 is a sectional view on the line 5—5 of Fig. 4.

Fig. 6 is a sectional view on the line 6—6 of Fig. 4.

Fig. 7 is a top plan view showing a modification.

Fig. 8 is a sectional view on the line 8—8 of Fig. 7.

Referring to Fig. 1, this shows a blank which is made of wood, or other suitable material which can be shaped according to any well known method.

Said blank has a handle portion 1, and an integral fork portion, said fork portion having a rounded base and also having legs 2 and 2a.

The base of said fork portion is thicker than the legs 2 and 2a of said fork portion. The rounded base of said fork portion is provided with shoulders 5 and 5a which may be equal to each other. The fork portion is also provided with a notch or shoulder 3.

The drawings are generally to scale, and they can be referred to, for additional details.

The inner wall A of the base of the fork, is preferably a true circular arc, so as to have the desired arch-shape, which combines maximum strength with minimum lightness.

A three-way nut member N is provided in a suitable recess 6, which is formed in one face of the blank. Said recess 6 may extend from the upper surface of the blank, partially into said blank, so that the nut member N can be placed in position as indicated in Fig. 4 for example, and the recess can then be closed by means of a suitable plug or the like. Said nut member N is provided with three internally threaded sockets which may make equal angles with each other.

The outer side wall of the blank is also formed with grooves or recesses G, as indicated in Figs. 1, 2, 3, and 4.

The first operation in forming the racket, is indicated generally in Fig. 3. The legs 2 and 2a are steamed or otherwise treated, until they can be readily bent. The leg 2 is first bent into the shape shown in Fig. 3. The leg 2a is then bent around the leg 2, until the end of the leg 2a enters the notch 3 which has been formed in the member 2. The adjacent surfaces of the legs 2 and 2a can be connected by means of any suitable adhesive. This gives the necessary shape to the frame of the racket, while securing great strength and great lightness. The inner and outer surfaces of the head of the frame are substantially smooth and continuous.

Referring to Fig. 4, a reinforcing member 8, which is partially generally indicated in dotted lines in Fig. 3, is then bent around the head of the frame, until the ends of said member 8 abut the shoulders 5 and 5a. The reinforcing member 8 may be connected to the frame, if desired, by means of any suitable adhesive. It will be noted that the head of the frame is formed by bending the blank, in a direction away from the handle-portion 1 of the blank.

A reinforcing member 9, having the shape shown in Fig. 4, is now applied to the handle 1 and to the head of the frame. This can be done by bending the reinforcing member 9 first around the head of the frame, and then at the side-walls of the handle 1.

These parts of the device can be made of wood, which can be shaped readily, when the wood has been steamed or otherwise softened. A weight W is located at the base of the handle 1.

Screws 12, 12a and 12b are then caused to enter the three sockets of the nut member N, and the heads of said screws are countersunk in the adjacent members. Said screws 12, 12a and 12b serve firmly to connect the reinforcing member 9 to the frame of the racket. Finishing and ornamental members 10, which may be made

of any suitable material can be connected to the outer wall of member 9. Additional straps 11, which can be made of wood or fiber, or other suitable material, are used for connecting the parts 2, 2a, 8, 9, and 10 to each other.

As shown in Fig. 5, the member 9 is formed with tongues 9a, which enter the recesses or grooves G, thus preventing any shifting or dislocation of member 9 relative to the blank.

The usual racket cords, made of the usual material are not shown, since they can be mounted in the head of the frame in the well known manner.

The embodiment shown in Fig. 7 can be made of "Bakelite" or other suitable material, which can be molded or otherwise readily shaped. The blank shown in Fig. 7 takes the place of the blank shown in Fig. 3, and the additional members shown in Fig. 4 are then added to the blank shown in Fig. 7, in order to reinforce and complete the same.

I have shown preferred embodiments of my invention, but it is clear that numerous changes and omissions can be made without departing from its spirit.

I claim:

1. A tennis racket comprising a frame having a handle which is integral with a head portion, said head portion being closed and having its outer end comprising bent and overlapping members, the outer side wall of one of said members having a notch in which the end of the other of said members is located, a first reinforcing member which abuts a portion of the outer side wall of said head, said outer side wall of the head having shoulders against which the ends of said first reinforcing member abut, and a second reinforcing member which abuts the outer side wall of the first reinforcing member and which also abuts the side walls of the handle.

2. A tennis racket comprising a frame having a handle which is integral with a head portion, said head portion being closed and having its outer end comprising bent and overlapping members, the outer side wall of one of said members having a notch in which the end of the other of said members is located, a first reinforcing member which abuts a portion of the outer side wall of said head, said outer side wall of the head having shoulders against which the ends of said first reinforcing member abut, and a second re-

inforcing member which abuts the outer side wall of the first reinforcing member and which also abuts the side walls of the handle, the inner end of the head of the frame having a three-way nut-member located therein, and screws which pass through said second reinforcing member and which enter two of the sockets of said nut-member, and a third screw which enters the third socket of said nut-member, said third screw being located in the inner end of the head of said frame.

3. A tennis racket comprising a frame having a handle which is integral with a head portion, said head portion being closed and having its outer end comprising bent and overlapping members, the outer side wall of one of said members having a notch in which the end of the other of said members is located, a first reinforcing member which abuts a portion of the outer side wall of said head, said outer side wall of the head having shoulders against which the ends of said first reinforcing member abut, and a second reinforcing member which abuts the outer side wall of the first reinforcing member and which also abuts the side walls of the handle, the outer wall of said frame having recesses and the second reinforcing member having tongues which fit in said recesses.

4. A tennis racket frame having a handle portion and having a head portion, said head portion comprising bent and overlapping arms projecting from said handle portion, the outer side wall of one of said arms having a notch in which the end of the other of said arms is locked.

5. A tennis racket comprising a frame having a handle portion and a head portion, said head portion comprising bent and overlapping arms projecting from said handle portion, said frame having grooves in the side walls thereof, and a reinforcing member extending around the side walls of said head and of said frame, said reinforcing member having tongues which enter said grooves, said reinforcing member being connected to said frame.

6. A tennis racket frame formed from a blank having a U-shaped body portion and a handle dependent from the base of said body portion, the projecting arms of said body portion being overlapped into closed position.

JOSÉ LUIS CONSIGLIO.
